INVENTOR

UNITED STATES PATENT OFFICE

103,866

DESIGN FOR A RECEPTACLE FOR BATTERIES OR SIMILAR ARTICLES

Henry Brunjes, Glendale, N. Y., assignor to
American Hard Rubber Company, New York,
N. Y.

Application February 10, 1937, Serial No. 67,561

Term of patent 7 years

To all whom it may concern:

Be it known that I, Henry Brunjes, a citizen of the United States and a resident of Glendale, in the county of Queens and State of New York, have invented a new, original, and ornamental Design for a Receptacle for Batteries or Similar Articles, of which the following is a specification, reference being had to the accompanying drawing, forming a part thereof, and in which:

Fig. 1 is a front elevation, and

Fig. 2 is an end elevation of a receptacle for

containing batteries or similar articles embodying my new design.

The end and side views not shown in the drawing are substantially the same design as the end and side views shown in perspective.

I claim:

The ornamental design for a receptacle for batteries or similar articles, as shown, and described.

HENRY BRUNJES.
